A. BELZ

WINDING MACHINE

Filed April 6, 1923

Inventor:

Albert Belz,

By *Henry M. Jr.*

Atty

UNITED STATES PATENT OFFICE.

ALBERT BELZ, OF UNTER-GOLDACH, SWITZERLAND.

WINDING MACHINE.

Application filed April 6, 1923. Serial No. 630,342.

To all whom it may concern:

Be it known that I, ALBERT BELZ, a citizen of the Republic of Switzerland, residing at Unter-Goldach, Ct. St. Gall, Switzerland, have invented certain new and useful Improvements in Winding Machines, of which the following is a specification, reference being had therein to the accompanying drawing.

10 The present invention relates to improvements in winding machines and particularly to winding machines for the manufacture of bobbins having paper cores. That is to say the machine first makes the paper 15 core, tube or quill, and then winds the thread upon it, delivering a full or loaded quill ready for use in the embroidery or other machine.

Winding mandrels provided with one slot 20 are known into which slot a strip of paper is introduced for manufacturing spools or bobbins with paper cores.

The output as well as the reliability of winding machines fitted with mandrels of 25 the above type is however reduced as the mandrel or the slot respectively has to be brought always into exactly the same position when starting to make a new bobbin, that is to say the mandrel has to be turned 30 sometimes through nearly a complete revolution.

This disadvantage is overcome by the subject matter of the present invention by providing the mandrel with a plurality of slots 35 so that the mandrel has to be turned through only an amount not greater than the pitch of the slots in order to be able to insert the paper, this turning motion being automatically effected by separate organs.

40 A constructional example of the subject matter of the present invention is illustrated on the accompanying drawings in which:

Fig. 1 is a side view of a winding machine,

45 Fig. 2 is a front view,

Fig. 3 is a section along the line III—III of Fig. 1,

Fig. 4 is a section along the line IV—IV of Fig. 3,

50 Fig. 5 is a section along the line V—V of Fig. 1 on an enlarged scale, and

Fig. 6 shows an enlarged perspective view of a detail.

In these drawings, 1 denotes the driving 55 shaft of the winding machine. On this driv-

ing shaft 1 are fixed the wheel 2 of a friction bevel gear 2, 3 and the worm 4 of a worm drive 4, 5. 6 denotes the winding mandrel which is provided with a number of longitudinal slots 6^a, as will be seen from Fig. 5. On the mandrel shaft the wheel 3 with the disc 7 secured thereto is fixed. The toothed disc 7 has the same pitch as the slots in the mandrel 6. The mandrel shaft is rotatably mounted in the support 8. The support 8 is adapted to be displaced along the rods 9, 10 and is provided with a roller 11 rotatably mounted on it, the roller bearing against the end facing of a cam disc 13 fixed to the shaft 12. Further the part 14 of a coupling is mounted on the shaft 12 so that it takes part in the rotation of the latter but is displaceable in the longitudinal direction of the shaft, a circular groove 15 being provided on the part 14. Rollers 17 mounted on the forked lever 16 engage with the groove 15. The lever 16 is turnable about the fulcrum pin 18 and is connected by means of a tension spring 19 to a lever 20 which is turnable about a pin 21. A roller 22 bearing against an end facing of the coupling part 14 is rotatably mounted on the lever 20. The lever 20 is further provided with an arm 23 which has a slot 24, engaging a bolt 26 fixed to a lever 25, the latter being turnably mounted about a pin 18. A compression spring 27 urges the lever 25 constantly against a sleeve 28 provided with a cut-out portion 28^a (Fig. 6). In alignment with the shaft 12 a shaft 29 is arranged to which the worm wheel 5 of the worm gear 4, 5 and the part 30 of the coupling are fixed.

A pin 31 is fixed to a bracket arm of the support 8 (Fig. 2), the pin 32^b serving as fulcrum to a lever 32. The free end of the lever 32 is situated below the toothed disc 7 and is provided with a prong 33 shaped as a wedge pointing in the upward direction and projecting into the path of the teeth of the disc 7. Further a wedge-shaped prong 34 is fixed to the lever 32 adapted to turn the toothed disc 7 when the point of a tooth of the latter contacts with the edge of the cam 33.

After the bobbin, the thread of which is wound upon a paper spool of the mandrel 6, is finished, a pull is exerted on the rod 28^b either by hand or by known means which are rendered operative when a determined

length of the thread has been wound upon the spool or when the bobbin has reached a determined thickness. Thereby the sleeve 28 is turned in the direction of the arrow A (Fig. 1) so that the lever 25 co-operating now with the cut-out part of the sleeve 28 is urged in the upward direction by the action of the compression spring 27, the arm 23 taking part in said upward turning movement, whereby the bolt 26 acts in the slot 24 thus causing the lever 20 to be turned in the clockwise direction. In this manner an axial displacement in the direction of the arrow B (Fig. 4) is imparted to coupling part 14 whereby the latter is brought in engagement with the constantly rotating coupling part 30 and is thus rotated, the shaft 12 being then coupled with the shaft 29. The roller 11 which up to this moment 10 has been resting in the lowest part of the end facing of the cam disc 13 moves on to the highest part of said facing of the cam disc 13 whereby a displacement of the mandrel 6 in the direction of the arrow C occurs, the supports 8 gliding along the rods 9, 10. Upon this axial displacement of the support 8 the rotating friction wheel 3 is brought out of engagement with the friction wheel 2 and is caused to bear against a spring loaded brake 35, whereby the mandrel 6 is brought to a stand-still. During the further slow rotation of the cam disc 13 in the direction of the arrow D (Fig. 2) the roller 11 leaves the highest point of the cam facing of the cam disc 13 and bears on the second highest point of said cam facing. Thereby the toothed disc 7 and the friction wheel 3 are moved away from the brake 35 but the wheel 3 is still out of engagement 20 with the friction disc 2. Now the cam facing 36 on the periphery of the cam disc 13 co-operates with the lever 32^a rigidly connected to the lever 32 and imparts to the latter a turning motion in the direction of the arrow E (Fig. 2), thereby the toothed disc 7 is turned by means of the prong 33 until the latter is able to penetrate into a space of tooth of the disc 7. As soon as this is the case one of the slots of the mandrel 6 is in a determined position, for instance in a position in which a strip of paper for making the paper spool can be inserted.

Upon further rotation of the cam disc 13 the lever 32^a runs off the cam facing 36 whereupon the cam 33 leaves the space of tooth. The support 8 with the mandrel and friction wheel 3 are moved towards the friction wheel 2 by the action of the spring 37 as the roller 11 has left the high parts of the cam facing on the disc 13 so that the friction gear 2, 3 is again operative, for instance for making the paper spool when the paper strip has been inserted into one of the slots of the mandrel during the time

the mandrel has taken up the determined position. The clutch parts 14 and 30 are thereafter disengaged, as the highest part of the cam facing 38 coacts with the roller 22 causes thereby a turning motion 70 of the lever 20, 23 in the anticlockwise direction, whereby the action of the slot 24 on the pin 26 causes the arm 24 to be depressed and the coupling part 14 to move away from the coupling part 30. The above described operation may then start again. 75

I claim:

1. In a winding machine, a driving friction wheel and a sliding frame, a slotted mandrel, a toothed disc and a driven friction wheel all mounted in and sliding with said frame, to move said driven friction wheel radially of said driving friction wheel, mechanism to slide said frame and mechanism brought into operation upon sliding said frame to arrest said disc and then position the disc to set one of the slots of the mandrel in receiving position. 80

2. In a winding machine, a driving friction wheel and a sliding frame, a slotted mandrel, a toothed disc and a driven friction wheel all mounted in said frame and moving therewith, to move the driven friction wheels radially of the driving wheel 90 into and out of operation therewith, a cam to shift said frame, clutch mechanism from which said cam is periodically driven, a brake shoe against which the driven wheel is moved when disengaged from the driving wheel and means operated by said cam to stop said disc and then position it to bring a mandrel slot into receiving position when said clutch is disengaged. 95

3. In a winding machine in combination, a mandrel adapted to make a spool by winding a strip of paper and provided with a plurality of longitudinal slots into one of which the end of a paper strip is to be inserted, a shaft to which said mandrel is fixed, a frame part in which said shaft is rotatably mounted, and adapted to be displaced in the axial direction of said mandrel, a driving shaft, a friction gear interposed between said driving shaft and said mandrel shaft, said friction gear being rendered inoperative by a displacement of said frame part, a toothed disc coaxially arranged with said mandrel and having a number of teeth corresponding to the number of slots in said mandrel, a prong adapted to enter into a space of tooth of said disc, a swingably arranged lever carrying said prong on its free end, a cam disc, means operatively connected to said lever and co-operating with said cam disc for causing said prong to enter into a space of a tooth for fixing the mandrel in a position in which a slot occupies a determined position, and further means adapted to control the operation of said first means and to cause a dis- 100

placement of said frame part for rendering said friction gear inoperative previous to causing the action of said prong.

4. In a winding machine, in combination, a mandril adapted to hold a spool and provided with a plurality of longitudinal slots, a toothed disc coaxially arranged with said mandril, and having a number of teeth corresponding to the number of slots in said mandril, a prong adapted to enter into a space of tooth of said disc, a swingably arranged lever carrying said prong on its free

end, a cam disc, means operatively connected to said lever and co-operating with said cam disc for causing said prong to enter 15 into a space of a tooth for fixing the mandril in a position in which a slot is in a determined position, and further means adapted to control the operation of said first means.

20 In testimony whereof I affix my signature.

ALBERT BELZ.
